DISPLAY STAND

David A. McCowan, Toronto, Ontario, Canada

Application August 6, 1949, Serial No. 4,342

Term of patent 14 years

(Cl. D80—9)

To all whom it may concern:

Be it known that I, David A. McCowan, a citizen of the Dominion of Canada, residing at Toronto, in the county of York, Province of Ontario, Canada, have invented a new, original, and ornamental Design for Display Stand, of which the following is a specification, reference being had to the accompanying drawing, forming part thereof.

The sole figure is a perspective view of a display stand, showing my new design, and showing particularly the top, the front, and one side thereof.

The side of the display stand not illustrated in the drawings is identical to the side shown whereas the rear thereof is open.

I claim:

The ornamental design for a display stand, as shown and described.

DAVID A. McCOWAN.
